(57) **CLAIM**

The ornamental design for a hand acupoint clip fixing bracelet, as shown and described.

DESCRIPTION

FIG. 1 is a front elevational view of a hand acupoint clip fixing bracelet showing my new design;
FIG. 2 is a rear elevational view thereof;
FIG. 3 is a left side view thereof;
FIG. 4 is a right side view thereof;
FIG. 5 is a top view thereof;
FIG. 6 is a bottom view thereof;
FIG. 7 is a top, front and right side perspective view thereof; and,
FIG. 8 is a bottom, left and rear side perspective view thereof.

The broken lines in the drawings illustrate portions of the hand acupoint clip fixing bracelet which form no part of the claimed design.
